UNITED STATES PATENT OFFICE.

NORMAN J. HOAG AND HENRY E. VOSBURGH, OF SKANEATELES, NEW YORK; SAID VOSBURGH ASSIGNOR OF ONE-THIRD TO SAID HOAG.

SPARK-PLUG.

1,120,384.

Specification of Letters Patent.

Patented Dec. 8, 1914.

Application filed December 26, 1913. Serial No. 808,697.

To all whom it may concern:

Be it known that we, NORMAN J. HOAG and HENRY E. VOSBURGH, citizens of the United States, residing at Skaneateles, in the county of Onondaga and State of New York, have invented certain new and useful Improvements in Spark-Plugs, of which the following is a specification.

This invention relates to sparking or igniting plugs for use in connection with internal combustion engines for electrically igniting the explosive gases in the engine cylinders, and has for its object to provide novel, simple and effective means for preventing the accumulation of oil, soot, or carbon in the neighborhood of the sparking points.

A further and particular object is to provide a coiled heating element between the outer casing or shell and the central conductor for burning the oil or smoke after each explosion, and thus prevent the accumulation of soot or carbon, which frequently causes the short-circuiting of many of the old styles of plugs. And a further object is to provide novel and simple means for securing the coiled heater in place.

In the accompanying drawing, Figure 1 is an elevational view of the complete plug; showing the heating element coiled around the insulating envelop of the central electrode. Fig. 2 is a central longitudinal section of the same. Fig. 3 is a similar sectional view; showing certain modifications. Fig. 4 is a broken elevation of the plug illustrated in Fig. 1; showing the spiral groove in the insulation to receive the heating coil. Fig. 5 is a bottom end view of the plug of Fig. 1. Fig. 6 is a similar view of the plug shown in Fig. 3. Fig. 7 is a broken elevation of the same with the coil omitted. Fig. 8 is a broken section; showing still another modification.

So far as we are aware the majority of the spark plugs employed for igniting the gases in internal combustion engines are what is commonly known as "chambered plugs," wherein there is provided adjacent the sparking end of the plug a chamber or cavity, whose principal function is to gather the soot or carbon, which results from the smoke of the explosion in the engine cylinder, the said chambers being so disposed as to draw the carbon away from the sparking points or terminals for preventing short

circuiting and the consequent failure of the plug.

Our improved spark plug is solid throughout its length, which greatly simplifies and cheapens its construction and also adds to its life.

The detailed description of our invention follows:

In the drawing, 2 represents the outer conducting shell or casing, which is bored out centrally and which is threaded at one end for attachment to the engine cylinder (not shown), while the other end is preferably made hexagonal to receive a wrench for applying and removing the plug. 70

3 represents a plurality of electrodes or terminals, which are carried by, and project from, the threaded end of the shell 2.

4 represents the central conductor, which comprises a rod or bar of steel or other suitable conducting metal, one end of which is threaded at 5 for receiving nuts 6 and 7. 75

8 represents a tubular insulating part preferably mica, which surrounds the rod 4 intermediate its ends, and which completely fills the bore of the shell 2, and insulates the shell from the rod 4. The lower end of the rod 4 is enlarged to provide a relatively broad head 9, which supports a number of electrodes or spark terminals 10, the ends of which are positioned near the free ends of the electrodes 3, and at which points the sparking occurs. The end 9 of the central conductor 4 is spaced a considerable distance below the threaded end of the casing 2, and passes through an enlarged insulating part 8', preferably cylindrical, and this part may comprise an extension of the tube 8. 80

12 represents a similar mica cylinder which encircles a portion of the rod 4 beyond the opposite end of the shell 2. 90

The shell 2, rod 4, and the insulators 8, 8' and 12, are all held in the assembled position by the nut 6, which bears upon a washer 13, as best seen in Figs. 1 and 2. 100

The electric current passes along or through the rod 4 from the wire 14, and from the head 9 to the terminals of electrodes 10. The current then jumps the gaps between the electrode 10 and the electrodes 3, and creates the spark which ignites the charge of gas in the engine cylinders, and from the electrodes 3 the current passes through the shell 2 to the engine cylinder in the usual way. 110

To prevent the smoke which results from each explosion of the gas in the engine cylinder from reaching the insulation 8', disposed between the head of the conductor 9 and the casing 2, as well as the consequent gathering thereon of carbon, we provide a wire coil 15, preferably comprising a metal which will attract and stand a high temperature, such as nickel or nickel-steel, the said 5 wire being coiled around the insulation 8', as shown in Figs. 1 and 2. The coil 15 is preferably substantially the length of the mica 8' and its upper end preferably rests against the end of the casing 2, but the said 10 coil is not intended to be a conductor of the current which effects the sparking, and for this reason the said coil is kept away from both the electrodes 3 and 10, which are relied upon entirely to carry the current. The coil 15 is employed only for attracting the heat 15 from the explosion chamber of the engine, and for consuming or burning up all smoke, oil or soot which approaches the portions of the plug which projects below the casing 2. 20 The coil-heater is close enough to the electrode 3 to effectually prevent, when heated up, any accumulation of smoke or soot on the said parts.

In practice, when the engine is working, 25 the temperature of the engine cylinder is sufficiently high to make the coil 15 red-hot, and while in this condition all smoke, soot or oil which touches the said coil, or the insulation within the coil are instantly consumed, so that after long intervals of running of the engine, there is no trace of carbon or soot on either the coil or the sparking end of the plug.

The coil 15 may be secured in place around 30 the insulation 8' in any suitable manner, but we prefer to attach the said coil by means of a spiral groove 16 which is formed in the said insulation, the coil being screwed in place like a nut, as best seen in Figs. 2 and 4.

Fig. 3 illustrates a modification, which 35 consists of providing a cone shaped insulator 11 about which is disposed a bee-hive coil 15', which is held in place by a circumferential groove 16' (see Fig. 7), preferably 40 formed adjacent the casing 2' which receives the top convolution of the coil. The electrodes 3' in this view are shown bent so as to bring their free ends close to the ends of the electrodes 10, and yet not contact with 45 the said coil. The outer ends 17 and 17' of the coils 15 and 15' are preferably disposed as shown in Figs. 5 and 6, at the farthest point from the ends of the electrode 10, so as to compel the sparking to take place at the 50 ends of the wires 3 and 3', rather than between the coil and the head of the central conductor, as described.

Fig. 8 illustrates a slight modification of 55 the coil 15, and consists of providing a tine 18, which is driven into a hole in the lower

end of the shell 2, for holding the coil in place, and especially for preventing the coil from being jarred loose and descending or otherwise coming into contact with the electrodes 3 and 10. The coils 15 and 15' may be 60 made in any suitable manner, but the spaces between the convolutions should not be less than one-thirty-second, nor greater than three-thirty-seconds of an inch, if these spaces are greater or less than described, 65 carbon from the smoke and reek will gather on the portion of the plug extending below the shell 2, and interfere with the working of the plug.

Having thus described our invention, 70 what we claim as new and desire to secure by Letters Patent, is—

1. In a spark plug, the combination with the outer shell and a plurality of electrodes projecting from one end of the shell, of a 75 central conductor passing through said shell, one of its projecting ends having a head provided with a plurality of electrodes disposed so as to provide narrow spark gaps between the corresponding electrodes of the 80 shell, an insulating material separating said conductor from said shell and surrounding the portion of the conductor between said head and the end of the shell, and a heating-coil wound around the said insulation between said head and said shell and spaced 85 from all of said electrodes.

2. The combination of a solid-spark-plug comprising an outer and an inner conductor arranged concentrically, the outer conductor 90 provided with depending electrodes, the inner conductor having a head spaced from the other conductor, which supports an electrode the opposite ends of which approach 95 close to the first electrodes, an insulator separating said conductors and provided with a spiral groove extending from said head toward said outer conductor, and a smoke-consuming coil partially embedded in said 100 groove and spaced from all of said electrodes.

3. In a solid spark-plug, the combination with the hollow shell carrying a plurality of electrodes, of a central conductor passing through said shell, one end of said conductor having a head disposed between the free 105 ends of the electrodes carried by said shell, an electrode piercing said head at right angles to said conductor, the opposite ends of said electrode disposed adjacent the free 110 ends of the first electrodes, an insulating material surrounding said conductor and separating it from said shell, and a smoke-burning coil encircling the portion of said insulation extending between said head and 115 the adjacent end of said shell.

4. In a solid spark-plug for explosive engines, the combination with inner and outer conductors, the inner conductor having a head projecting beyond the outer conductor, 120

of an insulating material substantially surrounding the inner conductor and completely closing the bore of the outer conductor, terminals carried by the outer conductor and disposed parallel to said inner conductor, the free ends of said terminals disposed adjacent said head, spark-terminals carried by said head and approaching close to said first terminals, a coiled heating member 5 coiled around the insulation extending between said head and the end of said outer

conductor adapted for attracting the heat and consuming the smoke and soot produced by explosions in the engine.

In testimony whereof we affix own signatures in presence of two witnesses.

NORMAN J. HOAG
HENRY E. VOSBURGH.
